US00D810279S

(12) **United States Design Patent** (10) **Patent No.:** **US D810,279 S**
(45) **Date of Patent:** **** Feb. 13, 2018**

(54) **INJECTOR DEVICE**

- (71) Applicant: **MEDIMOP Medical Projects Ltd.**, Ra'anana (IL)
- (72) Inventors: **Oz Cabiri**, Macabim-Reut (IL); **Reuven Y. Filman**, Netanya (IL); **Boris Degtiar**, Modiin (IL); **Ofer Zick**, Tikva (IL)
- (73) Assignee: **MEDIMOP MEDICAL PROJECTS LTD.**, Ra'anana (IL)
- (**) Term: **15 Years**
- (21) Appl. No.: **29/605,056**
- (22) Filed: **May 23, 2017**
